UNITED STATES PATENT OFFICE.

JOHN F. KELLY, OF TRENTON, NEW JERSEY, ASSIGNOR TO THOMAS MADDOCK'S SONS COMPANY, OF TRENTON, NEW JERSEY, A CORPORATION OF NEW JERSEY.

WATER-CLOSET BOWL.

1,198,454.

Specification of Letters Patent. Patented Sept. 19, 1916.

Application filed July 9, 1915. Serial No. 38,840.

To all whom it may concern:

Be it known that I, JOHN F. KELLY, a citizen of the United States, and a resident of Trenton, in the county of Mercer and 5 State of New Jersey, have invented certain new and useful Improvements in Water-Closet Bowls, of which the following is a specification.

My present invention relates to the construction of water closet bowls made of porcelain or other similar material, the object being to provide a closet which is silent in operation.

It has been the aim for many years in this art to reduce the noise attendant upon flushing the bowl by varying the manner of supplying the water to the various parts and such efforts have met with more or less success in practice. Part of the noise comes 10 from the jet holes in the flushing rim as the air is suddenly forced out due to the sudden in-rush of water causing a hissing sound and further noise is characterized by a gurgling sound as the level of the water in the 15 well of the bowl drops lower than the lip in the uprising leg of the siphon when the bowl is being washed out. By constructing 20 a closet bowl in accordance with this invention such noises are reduced to a minimum and to a much greater extent than has 25 heretofore been accomplished.

The invention consists in the improved construction or formation of water closet bowl hereinafter more particularly described and then specified in the claims.

In the accompanying drawings, Figure 1 is a central longitudinal section through a water closet bowl constructed in accordance with this invention. Fig. 2 is a vertical 40 cross-section taken on the irregular line 2-2 Fig. 1. The line of the cross-section where it passes through the top of the bowl is also indicated at 2-2 in Fig. 3. Fig. 3 is a horizontal section taken on the line 3-3 45 Fig. 1.

1 indicates the closet bowl proper preferably formed as an integral porcelain structure and 2 the well containing a body of water the level of which is controlled by a 50 dam 3 connecting the upward leg 4 and the downward leg 5 of a siphon discharge of any desired type.

6 indicates the inlet opening to which is connected the water supply pipes through

which water is fed to the well 2 and the 55 usual flushing rim 7, the flushing rim being provided with outlet jets or openings 8 as is well known in the art.

9 indicates the water reservoir compartment, the lower part of which is located below the well 2 and communicates therewith by means of the usual siphon jet 10 so arranged, as usual, that when the flow of water is started the jet directs the water from the reservoir 9 up through the siphon leg 4 and 60 the contents of the well 2 are emptied through the siphon discharge 4, 5. The reservoir 9 extends upward between the up and down legs 4 and 5 of the siphon.

11 and 12 indicate channels or passages 70 formed at each side of the bowl at the rear and preferably as an integral part of the bowl. The channel or passage 11 connects the inlet 6 with the reservoir 9 and jet 10 through a port 25 at the upper end of the 75 channel and a port 16 at the lower end while the channel or passage 12 through a port 17 at the lower end and port 26 at the upper end connects the reservoir 9 with the flushing rim 7. The port 26 establishes communication between the channel 12 and a chamber 14 which in turn communicates with the flushing rim proper. The channels 11 and 12 and the ports 25 and 26 are separated from each other at their upper ends by a 80 partition 15 which prevents the supply water entering the channel 12 direct from the inlet 6 and causes all of the supply water delivered to the inlet to pass first into the channel 11.

By this construction it is necessary for the water in order to reach the flushing rim to first pass through some part of the reservoir compartment 9 with which the siphon jet 10 communicates and therefore it is the 95 same water that passes into the reservoir that supplies the rim 7. By causing the incoming water to first enter the reservoir compartment preferably below the jet, the reservoir acts as a muffler to check the speed 100 of the inrushing water and permits it to rise gradually up the passage 12 and to the rim whereby it slowly forces the contained air in the rim through the openings 8 and prevents the air mixing with the water as well 105 as prevents the water compressing the air, both of which cause the well known hissing noise. When the air is allowed to escape

easily as by the gradual rise of the water in the passage 12 slowly forcing the air ahead of it the hissing sound is eliminated.

I also preferably form a transverse passage 18 in the lip 19 at the entrance to the upward leg 4 of the siphon which passage communicates preferably with both the channels 11 and 12 and obtains water therefrom. The passage 18 may be provided in any desired manner by forming it in the material of the bowl or by molding a metal or other pipe in the material or otherwise. A plurality of small outlet openings or jets 20 are provided in the bottom of the passage 18 so that water in said passage will discharge or spray downwardly toward the bottom of the well 2, the water from the openings preferably merging together and forming a curtain of water indicated at 21. If desired when separated openings are used they may be flared outwardly at the exits to more effectually merge the individual streams. When the transverse passage 18 is provided the supply water, when admitted to the inlet, is fed to the passage 18 from the channel 11 and thence sprays downwardly or transversely across the opening to the siphon leg 4 so that when the level of the water has fallen below the lip 19 due to the action of the jet 10 and siphon 4, 5, any space which might otherwise occur between the water level and the lip 19 is sealed by the curtain 21 and the gurgling noise which usually takes place due to the dropping away of the water from the lip 19 is avoided. The curtain of water may be used either with or without the particular manner of feeding the water to the rim hereinbefore described.

It is thought the operation of the closet is obvious. The water when introduced at the inlet 6 passes down the channel 11 and to the reservoir 9. Some of it is forced up through the jet 10 to assist in siphoning the well 2 while part of it rises up the channel 12 to the flushing rim 7, gradually forcing the contained air ahead of it through the rim openings 8. At the same time, when the feature is incorporated, water enters the passage 18 and is discharged through the openings 20 forming the curtain 21 across

the entrance to the siphon leg 4 as heretofore described.

It will be understood that the invention is not limited to the exact arrangement or 55 details of construction as shown and described but that various departures may be made from the same without departing from the spirit of the invention as expressed in the appended claims. 60

What I claim as my invention is:—

1. A water closet bowl provided with a siphon discharge and a transverse passage located at the entrance to the siphon and adapted to discharge a curtain of water laterally across said entrance when the closet is operated. 65

2. A siphon-jet water-closet bowl provided with a transverse passage adapted to receive water and discharge it downwardly 70 across the entrance to the siphon when the closet is operated.

3. A water closet bowl, provided with a well, a siphon discharge, a transverse passage located at the entrance to the siphon 75 and adapted to receive water and openings in the bottom of said passage through which the water is discharged in a manner adapted to choke the air entering the siphon as the level of the water in the well lowers during 80 the operation of the closet.

4. A water closet bowl having a well, a reservoir below the well, a flushing rim, a siphon discharge, a siphon jet connecting said well and reservoir, a chamber adapted to supply water to said reservoir, means adapted to supply water to said rim only after passing through said reservoir and a transverse water passage communicating with said chamber and adapted to discharge 90 water transversely across the entrance to the siphon discharge as the level of the water in the well lowers during the operation of the closet.

Signed at Trenton, in the county of 95 Mercer and State of New Jersey, this 7th day of July, A. D. 1915.

JOHN F. KELLY.
